UNITED STATES PATENT OFFICE

ELI BLANCHETTE, OF DAYVILLE, KILLINGLY, CONNECTICUT

DESIGN FOR A BANJO OR SIMILAR ARTICLE

Application filed October 7, 1931. Serial No. 41,335. Term of patent 14 years.

To all whom it may concern:

Be it known that I, ELI BLANCHETTE, a citizen of the United States, residing at Dayville, Killingly, in the county of Windham and State of Connecticut, have invented a new, original, and ornamental Design for Banjo Or Similar Article, of which the following is a specification, reference being made to the accompanying drawings, forming a part thereof.

Fig. I is a perspective view of a banjo or similar article showing my new design;

Fig. II is a side elevation thereof;

Fig. III is a bottom plan view of same.

I claim:

The ornamental design for a banjo or similar article, as shown.

In testimony whereof, I affix my signature.

ELI BLANCHETTE.
